[57] CLAIM

The ornamental design for a beverage dispensing valve, substantially as shown and described.

DESCRIPTION

FIG. 1 is a front elevational view of a beverage dispensing valve, showing our new design;

FIG. 2 is a rear elevational view thereof;

FIG. 3 is an elevational left side view thereof, the right side being the mirror image of the left side;

FIG. 4 is a top plan view thereof; and

FIG. 5 is a bottom plan view thereof.

FIG. 1

FIG. 2

FIG.3

FIG.4
